TABULATOR STOP ASSEMBLY

Richard Braun, Hartford, and Gunther Kern, Cromwell, Conn., assignors to Royal McBee Corporation, Port Chester, N. Y., a corporation of New York

Application September 19, 1956, Serial No. 610,784

13 Claims. (Cl. 197—70)

This invention relates to tabulator stop assemblies of the kind used, for example, with typewriting or like machines. More particularly, the invention relates to improvements in the construction of stop assemblies of the kind comprising an elongated stop mount, such as a bar or the like, and a plurality of stops carried on the mount for movements selectively from retracted or ineffective positions to projected or operating positions.

It previously has been common to provide such constructions with cooperable detenting means on the stop mount and the individual stops for yieldably retaining the stops in set positions, either retracted or projected. In one well known class of such constructions, the stops have been provided with individual detent springs, which, because of the close positioning of the stops on the mount, necessarily have been quite small, and hence rather fragile, requiring replacement from time to time. It has also been proposed to provide a single deflectable member, such as a rod or coiled spring, extending longitudinally of a set of stops and being cooperable in common with all of them for detenting purposes. A long detenting rod used for such a purpose has the disadvantage that it is deflected generally over at least a substantial part of its length when it is subjected to the detenting action of a single stop being moved from retracted to projected position, or vice versa, with the result that the holding action of the rod on nearby stops is reduced and rendered less certain. A construction including a single elongated coiled spring as a detenting element cooperable with a complete array of individual stops, as previously proposed, has left much to be desired with respect to supporting the spring, and enabling removal of individual stops from the assembly. Examples of previously known constructions including detenting members common to a plurality of stops are shown in the patents to Steele 1,045,452; Myers 1,249,456; and Schremp 2,312,676.

An object of the present invention is to provide an improved tabulator stop assembly construction including an elongated detenting means cooperable individually with a plurality of selectively settable stops and in which the difficulties previously encountered are eliminated or minimized.

Another object of the invention is to provide a construction of the class referred to in which the detenting means comprises a flexible element such as a coiled spring, having the property of being locally deformable by the detenting action of a stop moved individually, so that the retaining effect of the detenting means on other stops will not be materially lessened.

Another object of the invention is to provide a construction of the character stated in which the elongated flexible detenting means is backed up substantially throughout its length by a cushion which contributes to localizing the deformation of the flexible detenting means to the immediate vicinity of an individually moved stop.

A further object of the invention is to provide an assembly of the kind referred to in which the parts are so arranged and connected together as to facilitate removal

2

of one or more stops from the stop mount without requiring that all of the stops be removed.

Other objects of the invention will become apparent from a reading of the following description of a preferred construction, the appended claims, and the accompanying drawings, in which:

Figure 1 is a fragmentary perspective view of a construction embodying the invention, some of the parts being shown in separated relation, some of the parts being shown in vertical section fore-and-aft of a typewriting machine, and others of the parts being broken away;

Figure 2 is a fragmentary view, partly in front elevation with some parts being shown in vertical section longitudinally or from side-to-side of the typewriting machine, and other parts being broken away for clarity of illustration;

Figure 3 is a fragmentary vertical section, fore-and-aft of the machine, with a tabulator stop and parts of a stop setting and resetting mechanism being shown in end elevation, the tabulator stop being shown in its retracted position in full lines and in its intermediate and projected positions in dotted lines, a main frame mounted stop blade being shown in its inactive position;

Figure 4 is a view similar to Figure 3, but showing the tabulator stop in its projected position and the frame mounted tabulator blade in its active or stop intercepting position; and

Figure 5 is a view similar to Figures 3 and 4, but showing a stop resetting mechanism in operating position for returning projected tabulator stops to their retracted positions.

Tabulator stop assemblies embodying the invention are adapted for use in connection with machines of different general constructions. For the purposes of illustration, a preferred construction in accordance with the invention is illustrated as being associated with mechanism of the kind customarily embodied in Royal 10-key decimal tabulating typewriting machines. Only enough of the machine organization, other than the tabulator stop assembly construction, is illustrated to exemplify one typical use of constructions embodying the invention. In the general organization of the illustrated machine components, an elongated tabulator stop mount A is incorporated in the travelling carriage of a typewriting machine so as to extend in the direction of carriage travel on the main frame, not shown. A plurality of tabulator stops B are supported on and spaced along the mount for movement transverse to the mount from retracted positions in which they are incapable of effecting any tabulating control function to projected positions in which they are cooperable with mechanism carried by the main frame for arresting the carriage at the selected tabular position. The stops B are movable selectively from their retracted to their projected positions by a stop setting lever C adapted to be rocked by suitable actuating mechanism, not shown, from its position shown in full lines in Figure 3 counterclockwise progressively to the positions shown in dotted lines in Figure 3 to engage the adjacent vertical edge of a stop B which has been disposed in alignment with the setting lever C by positioning the carriage on the frame in a well known manner. When a stop has been set in its projected position as shown in dotted lines at B' in Figure 3 and in full lines in Figures 4 and 5, it is engageable with a selected one of the ten frame-mounted stop blades D which has been moved into the path of the projected stop B for intercepting the latter and bringing the carriage to rest in its tabulating position. Stops B which have been set in projected positions may conveniently be returned to retracted positions

60 through the agency of a stop resetting lever E equipped with a roller e engageable with the adjacent rear vertical edges of projected stops B when the lever E is rocked

clockwise as viewed in Figure 3 to the position shown in dotted lines in Figure 5; and the carriage is then moved along the frame, causing the projected stops to be wiped back, so to speak, by the roller *e* into their retracted positions.

The organization of components described generally above and its manner of operation are generally similar to the organization and operation of the 10-key decimal tabulating typewriter mechanism disclosed in the patent to Lewis C. Myers et al, 1,892,071, dated December 27, 1932.

The tabulator stop mount *A* comprises parallel spaced parts, in the form shown upper and lower toothed bars *1* and *2*, connected at their opposite ends respectively by plates, one of which is shown at *3* in Figure 1, as being secured to the bar ends by screws *4* and *5*. Each of the plates *3* is provided with a threaded rod or stem *6* which extends through an aperture *7* in the adjacent carriage frame end plate, one of which is shown at *8* in Figure 1. Nuts *9*, *9* threaded onto each rod *6* and screwed up against opposite sides of the associated end plate secure the mount *A* to the carriage frame.

The bars *1* and *2* of the mount are positioned with their toothed sides facing each other so as to provide pairs of oppositely disposed aligned grooves or slots *10* extending transversely of the mount for respectively receiving the individual stops *B*, one stop in each pair of aligned grooves. In this manner the stops are mounted for sliding transverse movement between retracted positions as shown in full lines in Figure 3 to projected positions as shown in dotted lines *B'* in Figure 3 and in full lines in Figures 4 and 5, in the latter of which positions the stops are interceptible by a selected and actuated frame mounted stop blade *D*.

The stops *B* are all of similar construction, each being formed on its upper exposed marginal edge *11* with a hump providing a detent *12*. Means, generally designated *F*, on the mount *A* is cooperable with the stops *B* and their detent means *12* for both retaining the stops against separation or removal from the mount, and for releasably holding the stops in their retracted or projected positions. In accordance with the invention, the stop retaining and detent cooperating means *F* comprises an elongated flexible means *13* extending longitudinally of the mount and in engagement along its bottom side with the stops *B*, and an elongated backing means *14* carried by the mount *A* in such a position as to back up the flexible means *13* along its top side and yieldably resist deflection of the latter upwardly or away from the stop marginal edges *11*. The flexible means *13* and backing means *14* are removably connected to the assembly by a retainer bar *15*, generally L-shaped in cross section, secured to the upper mount bar *1* by screws, one of which is shown at *16*, the bar *15* having a part *15a* which overlies the mount bar *1* and engages the top surface of the backing means *14* remote from the spring *13*, and a part *15b* spaced forwardly from the front surface of the bar *1* and extending downwardly alongside the backing means *14* and, preferably, the flexible means *13*.

Desirably, the flexible detenting means *13* is of unitary elongated construction, being formed, for example, as a one-piece coiled spring interposed between the stops *B* and the backing means *14* in a manner to be engaged by the backing means *14* substantially throughout the length of the spring *13*. The backing means *14* may also be of one-piece or unitary form, and is shown as being constituted by a single strip of cushioning material, for example soft rubber. Other similarly soft or yieldable materials, e. g. synthetics, having substantially the cushioning properties of soft rubber may also be used. The arrangement is such that the upper mount bar *1*, the retainer *15*, and the spring *13* together surround and confine the backing *14* so that any upward deformation of the spring *13* necessarily causes the rubber strip *14* to be compressed, as distinguished from being deflected.

The strip *14* and the part *15b* of the retainer project below the bottom surface of the mount bar *1* to an extent sufficient to be cooperable with abutments *17* and *18* extending upwardly from the stops *B* for preventing complete separation of the stops from the mount *A* and confining the stops to limited transverse movement between their retracted and projected positions. The stops *B* are, however, individually totally separable from the mount *A* by following a simple procedure. Any stop or stops *B* may easily be removed for replacement by simply detaching the screws *16* and retainer *15*, and lifting the spring *13* and backing strip *14* slightly, the other stops *B* being left undisturbed in the associated slots *10* in the mount *A*. The individual removal of separate stops is possible because of the positioning of the spring *13* exteriorly of and across the similarly disposed marginal edges *11* of the stops.

Normally, when no tabulating operation is called for, the stops *B* will be in the retracted positions shown in full lines in Figure 3 with the spring *13* engaging the left sides of the stop detents *12* and the lower portions of the abutments *17*. The cushioning strip *14* presses or holds the spring *13* against the stops *B* with sufficient force to prevent accidental movement of any stop detent *12* toward the left so that the stops *B* are effectively held in retracted positions. When a tabulating operation is to be performed, the stop setting lever *C* is operated to press the selected stop *B* toward the left as viewed in Figure 3, causing the stop detent *12* to cam the immediately adjacent and contacting part of the spring *13* upwardly as indicated at *13a* in Figure 2, and thus permitting the stop *B* to be moved completely to its projected position illustrated in full lines in Figures 4 and 5, the exact limit of the movement of the stop to its projected position being determined by engagement of the stop abutment *18* with the depending part *15b* of the retainer *15*. The stop having been set in its projected position, the right side of its detent *12* will be in contact with the spring *13* which, backed up and assisted by the cushioning strip *14*, will retain the stop against accidental displacement back to its retracted position.

Since the spring *13* is backed up by the cushioning member *14* throughout its entire length, it is not subjected to a general longitudinal stretching or deflection when traversed by a stop detent *12*, but is deformed only locally adjacent to the moving detent, the local deformation of the spring being resisted by the adjacent part of the cushioning strip *14*. Consequently, the retaining effect of the spring *13* upon the other stops, not being moved, is not disturbed or even substantially varied. Moreover, the deflection of the spring, localized because of being backed up by the cushion *14*, does not tend to open or separate normally contacting or substantially contacting adjacent spring convolutions at any point of engagement of the spring with any of the stops *B*.

The selected stop or group of stops *B* having been set for cooperation with the frame mounted tabulator stop fingers *D*, the tabulating operations may be performed in the usual and well known manner. So, too, resetting of the stops to their retracted positions may be performed in a known manner through the agency of the resetting device *E*.

The construction shown embodies the invention in a preferred form, but it is intended that the disclosure be illustrative rather than definitive, the invention being defined in the claims.

We claim:

- In a tabulator stop assembly, an elongated stop mount; a plurality of stops carried by said mount in spaced relation therealong and being movable transversely thereof between retracted and projected positions; detent means respectively on said stops; and means on said mount cooperable with said detent means for releasably holding said stops in selected positions, comprising an elongated flexible means carried by said mount and

extending longitudinally of said mount with one side of said flexible means engaging said detent means, and an elongated backing means of cushioning material carried by said mount and engaging said flexible means on the other of its sides along the length of said flexible means.

2. A tabulator stop assembly construction as set forth in claim 1 in which said flexible means comprises a coiled spring.

3. A tabulator stop assembly construction as set forth in claim 1 in which said backing means material has substantially the cushioning properties of yieldable rubber.

4. A tabulator stop assembly construction as set forth in claim 1 including means on said mount cooperable with said flexible means for surrounding and confining said backing means, the latter being compressible whereby said flexible means may be locally pressed into the confined backing means by the detent means on one of said stops when the latter is moved from one of its selective positions to the other.

5. A tabulator stop assembly construction as set forth in claim 1 in which said stops and said mount have cooperable abutments for limiting movement of said stops transverse to said mount.

6. A tabulator stop assembly construction as set forth in claim 1 in which said flexible means is constituted by a single one-piece coiled spring having its adjacent convolutions in contact with each other.

7. A tabulator stop assembly construction as set forth in claim 1 in which said backing means is constituted by a single one-piece strip of cushion material having substantially the cushioning properties of yieldable rubber.

8. A tabulator stop assembly construction as set forth in claim 1 in which said flexible means comprises a coiled spring and said backing means comprises a strip of cushion material having substantially the cushioning properties of soft rubber, said backing means contacting said flexible means substantially throughout the length of the latter.

9. In a tabulator stop assembly, an elongated stop mount; a plurality of stops carried by said mount in spaced relation therealong and being movable transversely thereof between retracted and projected positions; detent means respectively on said stops; means on said mount cooperable with said detent means for releasably holding said stops in selected positions, comprising an elongated flexible means carried by said mount and extending longitudinally of said mount with one side of said flexible means engaging said detent means, and an elongated backing means of cushioning material carried by said mount and engaging said flexible means on the other of its sides along the length of said flexible means; and means detachably secured to said mount for releasably retaining said flexible means and said backing means on said mount in cooperative relation to said stops.

10. A tabulator stop assembly construction as set forth in claim 9 in which said retaining means comprises an L-shaped bar having one part engaging said backing means along the surface thereof remote from said flexible means and another part extending alongside and being spaced from a surface on said mount and engaging a surface on said backing means, said backing means being substantially surrounded and confined by said flexible means, said retaining means, and said mount surface.

11. In a tabulator stop assembly, an elongated stop

mount; a plurality of stops carried by said mount in spaced relation therealong and being movable transversely thereof between retracted and projected positions; detent means respectively on said stops; means on said mount cooperable with said detent means for releasably holding said stops in selected positions, comprising an elongated flexible means carried by said mount and extending longitudinally of said mount with one side of said flexible means engaging said detent means, and an elongated backing means of cushioning material carried by said mount and engaging said flexible means on the other of its sides along the length of said flexible means; abutments respectively on said stops engageable with one of two means, namely: said flexible means and said backing means, for limiting movement of said stops transverse to said mount and for preventing removal of said stops from said mount; and means detachably secured to said mount for releasably retaining said flexible means, said backing means and said stops on said mount.

12. In a tabulator stop assembly, an elongated stop mount comprising two spaced parallel bars formed with pairs of aligned transverse slots; a plurality of stops mounted for transverse movement in respective pairs of slots between retracted and projected positions; detent means respectively on said stops; a backing strip of cushioning material; a retaining member detachably secured to one of said mount bars for holding said backing strip against said bar with one edge of said backing strip facing toward but being spaced from said stop detent means; and an elongated flexible member interposed between and engaging both said stops and said backing strip substantially throughout their lengths and thereby exerting force on said detents for holding said stops against transverse movement, both said flexible member and said backing strip being locally deformable by said stop detent means for enabling any selected stop to be shifted transversely from one position to the other without substantially diminishing the holding force exerted by said flexible member on other stops.

13. In a tabulator stop assembly, an elongated stop mount; a plurality of stops carried by said mount in spaced relation therealong and being movable transversely thereof between retracted and projected positions; detent means respectively on similarly disposed outer marginal edges of said stops; an elongated flexible means connectable to said mount to extend parallel to said mount transversely of said stops for cooperation with said detents to releasably hold said stops in selected positions; abutments on said stops respectively engageable with said flexible means when the latter is connected to said mount for preventing movement of said stops transverse to said mount sufficient to separate said stops from said mount; and means for detachably connecting said flexible means to said mount, said stops being individually separable from said mount when said flexible means has been disconnected from said mount.
